DISPLAY BOX FOR WATCHES OR THE LIKE

Arthur R. Botham, New York, N. Y., assignor to The Bulova Watch Company, Flushing, N. Y., a corporation of New York

Application January 2, 1958, Serial No. 49,116

Term of patent 7 years

(Cl. D80—5)

FIG. 1.

FIG. 3.

Fig. 1 is a front perspective view of a display box for watches or the like showing my new design, it being understood that the transparent faceted areas are continuous as indicated in Figs. 1 and 2, although only portions thereof are shown in detail for convenience of illustration; Fig. 2 is a front elevational view thereof, the rear being substantially plain; and Fig. 3 is a side elevational view of Fig. 1, the other side being the same as the side shown.

I claim:

The ornamental design for a display box for watches or the like, substantially as shown and described.
